WHEELLESS FOUR-TOOLS-IN-ONE DISK
IMPLEMENT

William Frederick McMahon, Riverside, Calif.

Application February 13, 1942, Serial No. 430,768

9 Claims. (Cl. 55—73)

My invention relates to disk harrows and more particularly to a wheel-less four-in-one disk implement constructed to perform the function of harrowing, ridging, furrowing and ditching.

Heretofore all disk harrows were mounted on wheels made an integral part of the disk harrow itself in order to provide means for adjusting the depth of penetration of the disks therein, or in the event the disk harrow was not so mounted on wheels then the entire weight of the latter construction came upon the very soil it was cultivating and said weight caused a plow-sole or hard-pan to form. These heretofore disk harrows were very inefficient constructions because they served to pack underneath the very soil they were cultivating on top. In the former mentioned construction, mounted on wheels, heavy and complicated adjusting mechanisms had to be resorted to and made an integral part of the disk harrow itself. This heavy adjusting mechanism obviously added weight to the respective heretofore disk harrows and increased the hardness of the plow-sole. Obviously, both of these heretofore types of construction were drawn by tractors having wheels but they were not constructed to be carried on the wheels of the tractors. My improved disk harrow is constructed so that its weight is carried on the wheels of the tractor which draws it and a new result, the elimination of the mentioned hard-pan or plow-sole, is provided thereby. I will hereafter use the term "wheel-less" to distinguish my improvement with its new result from that which was formerly used. All heretofore disk harrows, having wheels made an integral part thereof, regulated the depth of penetration of their disks in direct relationship with their said wheels and independent of the tractor wheels whereas, I regulate the depth of penetration of my disks in direct relationship with the tractor wheels and by so doing create my new result above mentioned. My improvement further resides solely in disk harrows having two parallel opposed gangs of disks and the conception of utilizing my respective disk harrow construction to do the work of ridging, middle-busting, furrowing and ditching without having to resort to extra elements from those used in the basic disk harrow and without departure from the basic mode of operation thereof and new result above mentioned.

Without my disk harrow construction of two parallel gangs of opposed disks I obviously could not convert the harrow into a furrower or a ridger or a middle-buster or a ditcher because

these disk implements require individual mounted disks in the harrow that they are converted from and no heretofore disk harrow had individual mounted disks.

5 It is an object of this improvement to provide a simple single construction unit which can be used to perform the work heretofore done by four or more disk implements.

It is also an object of this improvement to 10 provide a single disk unit capable of doing the work of furrowing, ridging, ditching and harrowing.

It is also an object of this improvement to 15 provide a disk implement comprising parts constructed to form a disk harrow and then, with no extra parts, it can quickly be made into either a ridger or a furrower or a ditcher and quickly reconverted into either of the four said implements.

20 A further object is to provide an efficient soil cultivating disk implement for use in orchard, field and vineyard work.

A further object is to provide a wheel-less disk 25 implement with a close-up hitch connected to a simplified hooking and power lift, adapted to provide even controlled soil penetration at any desired depth with least draft.

Another object of this improvement is to provide a simplified disk implement connection, 30 with a tractor, which will result in a minimum load, of the weight of the said implement, on the tractor lifting mechanism.

With these and other objects in view, the invention resides and consists in the construction 35 and novel combination and arrangement of parts hereinafter more fully described, illustrated in the accompanying drawings, and pointed out in the claims hereto appended, it being understood that various changes in the form, proportion, design, size and details of construction may be resorted to by those skilled in the art without departure from the spirit or intent of this invention.

Similar characters of reference denote like or 45 corresponding parts throughout the several figures of the accompanying drawings forming a part of this specification and upon which:

Figure 1 is a plan view of the disk implement arranged as a disk harrow.

Figure 2 is a plan view of the same disk implement arranged as a disk furrower.

Figure 3 is a plan view of the same disk implement arranged as a disk ridger.

Figure 4 is a plan view of the same disk implement arranged as a disk ditcher.

Figure 5 is a longitudinal side elevation showing the disk implement penetrated into the soil and the particular lifting linkage system and its method of connection with a tractor.

Figure 6 is a similar longitudinal elevation showing the disk implement raised out of the soil and the position of the lifting linkage system in this operation.

Figure 7 is a sectional elevation through the disk bearing assembly.

Referring in detail to the characters of reference marked upon the drawings, 8 represents a conventional tractor having a conventional power take-off shaft 9.

The well known elements comprising the operating mechanisms of a conventional tractor, viz., the engine, gear transmission, differential gearing, drive shafts, power take-off shaft mechanisms and/or hydraulic lifting mechanisms and the other various well known elements thereof, are not shown nor described because it is thought that they are so well known, that further illustration and/or description would be superfluous.

My improvement is, basically, a novel, new and distinct four-tools-in-one disk implement adapted to be used with conventional tractors having mechanical or hydraulic lifts.

It is also well known that various conventional lift-type tractors have various forms of lifting arm elements which serve to connect implements therewith, but the basic difference between them all exists mainly in size, form and proportion.

However a serious drawback to the said conventional lifting arm elements is that their particular design and construction serves to limit the lifting capacity of the respective various conventional hydraulic and/or mechanical lifting mechanisms incorporated as standard equipment in the various conventional tractors. While the drawbar horsepower of the said tractors is such that many commercial implements can be pulled, yet the lifting power of the hydraulic and/or mechanical lifts, on the conventional tractors, prevents or limits the use of said commercial implements. This feature hinders or stops many sales of conventional tractors with lifts. To overcome this limitation in the lifting of heavy implements, I have provided a novel construction of a lifting arm 10 which has a fulcrum 11 on a support 12 secured to the front axle support 13 of the tractor 8. Arm 10 will extend over the top of the rear axle housing 14.

The particular design of said arm 10 serves to permit, the conventional tractor lifting mechanism, to raise or lift several times more implement load, on the tractor, without having to resort to any mechanical changes in the conventional lifting mechanism. The application of simple lever mechanics to the arm 10, as shown in Figures 5 and 6 of the drawings, will prove the above statement.

As a statutory prerequisite of disclosing at least one known way to operate or actuate the arm 10, I have placed a worm 15 onto a conventional power take-off shaft 9. This worm 15 will drive a worm-wheel 16. Suitable clutch and reversing mechanism, not shown, would obviously be applied, to the worm 15, in order to regulate the clockwise or counterclockwise movement of the wormwheel 16.

Secured to the worm-wheel 16 is a crank 17 which serves to transmit the movement of said worm-wheel 16 to the main lifting arms 10. A slot 18, in arm 10, provides connection with crank 17. On the outer end portion 19 of arm 10, I

connect my improved disk implement 20. There will be two arms 10 each parallel to each other on the same vertical plane. They will move as a unit. In the vicinity of the rear axle housing 14, 5 I form a bridge-shape 21, in the arm 10. This bridge-shape 21 may obviously be eliminated and the arm 10 made straight if so desired.

Arm 10 is thus moved in an upward direction and/or downward direction, on fulcrum 11, by 10 the corresponding movement of crank 17 moved by the worm-wheel 16.

The only difference between the operation of this mechanical lift 16 and a conventional hydraulic lift is that, the crank 17, in a hydraulic 15 lift mechanism, would be actuated by a hydraulic piston instead of a worm-wheel 16.

A top connecting link 22 is solely provided to maintain a horizontal position to the disk implement 20 when it is operating in the soil. See 20 Figure 5 of the drawings. Connecting link 22 is secured on one end portion thereof to the tractor 8 by means of bracket 23 which is fastened to the top of the differential gear housing 24. On its opposite end portion, it is connected with the uprights 25 of the cantilever rigid-hitch 26 of the disk implement 20.

Disk implement 20 comprises a single steel 25 shape frame 27 to which a cantilever rigid-hitch 26 is connected. This cantilever rigid-hitch 26 extends over the tops of front gang 28 of disk blades 30 and serves to connect the frame 27 with the tractor 8. Cantilever rigid-hitch 26 provides a close-up hitch with the tractor 8 and prevents the disk implement 20 from pulling away from the tractor 8 on hillside work. A notable feature 30 of the cantilever rigid-hitch 26 is that it connects with the disk implement 20 at a place located between the both gangs of disk blades. This said hitch 26, while shown to be made up of steel 35 shapes, is rectangular in shape and it may be formed a steel casting if so desired. Cantilever rigid-hitch 26 permits the disk implement frame 40 27 to be offset to either side of it.

On the market, at the present day, there are 45 several makes of conventional tractors with hydraulic or mechanical lifts. These said conventional tractors all have similar connecting arms of various proportions. My cantilever rigid-hitch is formed a universal design for connection, to the various conventional tractors, without departure from the design thereof illustrated and with but slight changes in proportion only.

Disk implement 20 is as heretofore stated 50 really four tools in one. It may be called a kit of implements. Heretofore no disk harrow was adapted to be changed into a disk furrower or a disk ridger or a disk ditcher without the use of extra parts or otherwise. Nor was any disk furrower adapted to be changed into a disk harrow, nor a disk ridger into a disk furrower, nor a disk ditcher into a disk harrow, yet this is now disclosed by my four-in-one disk implement 20.

I am enabled to make these said four-tools-in-one by the reason of the construction of a single disk blade 30 mounted on a single disc blade bracket 31, which bracket 31 is individually secured to a single frame 27. Also by reason of the fact that each disk blade 30 has two fixed cutting angles, viz., a plow angle 32 and a suction angle 33. Eliminate either one of the said plow angle 32 or suction angle 33 and you would have an impracticable tool for a lift type disk implement. For example, by referring to Figures 2, 3 and 4 of the drawings, it will be noted that 55 in the event I had two blades secured to a single

bracket it would be impossible for me to make three other tools out of the disk harrow shown in Figure 1.

By this, four-in-one implement, great saving in material is accomplished, for example: In a conventional five-foot three inch offset disk harrow, which is the same size as the disk harrow shown in Figure 1 of the drawings, fourteen disk blades are used; in a conventional disk furrower, of similar size, six disk blades are used; in a conventional disk ridger, four disk blades are used; in a conventional disk ditcher, six disk blades are used. Therefore in the four conventional disk implements mentioned there would be some thirty disk blades used not mentioning other elements whereas, in my disk implement 20 there would be required but twelve disk blades needed to form any one of the above mentioned four tools. This amounts to a saving, in material, in disk blades alone, of about one hundred percent. Further there would be required three additional frames in the conventional implements, so in frame construction, it can be said, that my disk implement saves over three hundred percent in materials for frame construction.

With the use of one tractor, no farmer ever has the occasion to use any two, of the four, above mentioned implements at the same time.

In the disk implement 20, the number of parts required to make the disk harrow, are the maximum number of parts required for the said disk implement 20, in other words, no additional parts are necessary to make any one of the other three implements, viz., ridger or ditcher or furrower.

By referring to Figure 1 of the drawings, there is shown a five-foot three-inch disk harrow 34 comprising a front gang 28 of disk blades, six in number, and marked *g*, *h*, *i*, *k*, *l* and *m*. Each disk blade 30 is mounted on an individual bearing bracket 31. Each bracket 31 is individually secured to the central frame member 27. Running parallel to the said front gang of disk blades is a rear gang 29 of disk blades 30 having similar mountings and securement as the said front gang 28. Six disk blades also form this rear gang 29 and these are marked *a*, *b*, *c*, *d*, *e* and *f*. The said rear gang 29, of disk blades, is in staggered formation relative to the location of the front gang 28 of disk blades. Each disk blade 30 of the front and rear gangs has a fixed plow angle 32 and suction angle 33.

Referring to Figure 2. To quickly change the disk harrow 34 into a disk furrower 35 I simply remove the disk blades, of the rear gang 29, marked *b*, *d*, and *e* and the disk blades, of the front gang 28, marked *h*, *i* and *l*, together with their respective brackets 31. However, disk blade *a*, of the rear gang 29, is moved from its original position as shown by the dotted lines 51, and disk blade *m* is likewise moved from its original position as shown by the dotted lines 52. No other parts are added in this change over from a harrow 34 to a furrower 35 and the same identical frame 27 and hitch 26 is used therewith.

Using the harrow 34, in Figure 1, to illustrate the change over to a disk ridger 36 as shown in Figure 3; disk blades marked *a*, *b*, and *c* are removed from the rear gang 29, and disk blades marked *k*, *l* and *m* are likewise removed from the front gang 28, together with their respective brackets. No other change is necessary.

Using the harrow 34, in Figure 1, to illustrate the change over to a disk ditcher 37 as shown in

Figure 4; the disk blades marked *d*, *e*, and *f* are removed from the rear gang 29 and disk blades *g*, *h*, and *i* are removed from the front gang 28, together with their respective brackets. No other change is necessary.

To reconvert any of the implements back into any one of the other three tools, the necessary brackets 31 together with their respective disk blades 30 are merely replaced into their required position on the frame 27 to suit the tool desired.

Referring in detail to the single bearing bracket 31 which is arranged to give a set plow angle 32 and a suction angle 33 to a single disk blade 30, and by further reference to Figure 7 of the drawings; a preferred steel casting 38 serves to provide a bearing 39 which is angled to create a suction angle 33 to the said disk blade 30, while its base 40 serves to provide the plow angle 32 thereto, in its connection with the frame 27.

Into the bearing end portion 39, a removable bushing 41 is mounted and secured from longitudinal movement by means of a bolt and nut 42, which holds the bushing 41 to the bracket 31. A rotatable shaft 43 is mounted in the bushing 41 and it is limited in its longitudinal movement by the means of its head 44 bearing against the fixed bushing end 45. A cylindrical washer 46 is pressed onto the shaft 43 and it has relative rotation with said shaft. This shaft 43 may be welded to the washer 46, if it is so desired. Washer 46 has a large bearing surface 47 to take care of the end thrust set-up by the disk blade 30. A grease seal, for a dust-proof precaution, is provided by the outward extending cylindrical lip 48 of washer 46. Said washer 46 has a series of holes adapted to receive a series of plow bolts 49, which are provided to secure the disk blade 30 to the washer 46. This bolting 49 arrangement permits the disk blade 30, washer 46 and shaft 43 to rotate as a unit, while the bushing 41 is secured against rotation. A grease fitting 50 is provided for lubricating this bearing.

What I claim is:

1. In a disc harrow constructed to be pulled by a tractor and raised or lowered by a lift mechanism made part of said tractor; a steel shape; a series of forwardly and rearwardly extending individual brackets, comprising a single rotatable disc blade mounted on each bracket, and detachably secured to the steel shape to form a disc harrow formation of disc blades and thereby arranged to form either a furrower, ridger, or ditcher, formation of disc blades; a connection for connecting the steel shape to the tractor.

2. In a disc harrow constructed to be pulled by a tractor and raised or lowered by a lift mechanism made part of said tractor; a steel shape; a series of forwardly and rearwardly extending bearing brackets individually and shiftably mounted on said steel shape in a disc harrow formation being arranged to form a furrower formation; a single rotatable disc blade mounted on each said bracket, each said disc blade inclined vertically and horizontally; a connection from the said steel shape to the lift mechanism in the tractor.

3. In a disc harrow constructed to be pulled by a tractor and raised or lowered by a lift mechanism made part of said tractor; a series of forwardly and rearwardly extending individual brackets; each bracket having a single rotatable disc blade mounted thereto; a bar detachably secured to and supported by the said brackets and blades; said bar constructed to provide a disc harrow formation of disc blades or a disc furrower

75

formation of disc blades; a connection to the lift mechanism of the tractor.

4. In a disc harrow constructed to be pulled by a tractor and raised or lowered by a lift mechanism made part of said tractor; a series of forwardly and rearwardly extending individual brackets; each bracket comprising a single rotatable disc blade; each disc blade inclined vertically and horizontally; a bar detachably secured to and supported by the said brackets; a hitch, to the lift mechanism of the tractor, shiftably mounted on said bar; said bar constructed to provide the disc harrow formation of disc blades and to permit conversion of the disc harrow formation into a disc furrower formation of disc blades and to reverse the said formations.

5. In a disc harrow constructed to be pulled by a tractor and raised or lowered by a lift mechanism made part of said tractor; a series of forwardly and rearwardly extending bearing brackets; a single rotatable disc blade inclined vertically and horizontally and mounted on each said bracket; a bar detachably secured to said brackets; a hitch, to the lift mechanism of the tractor, mounted on said bar; said disc harrow formation of disc blades constructed to permit conversion therefrom to provide a disc furrower formation of disc blades or a disc ridger formation of disc blades or a disc ditcher formation of disc blades and to permit a reversal of the said formation of disc blades into each others formation.

6. In a disc harrow constructed to be pulled by a tractor and raised or lowered by a lift mechanism made part of said tractor; a series of for-

wardly and rearwardly extending individual bearing brackets; each bracket providing a mounting for a single rotatable disc blade being inclined vertically and horizontally; a bar detachably secured to said brackets and constructed to provide a disc harrow formation to the disc blades and to provide a conversion arrangement of disc blades to form either a disc furrower formation of disc blades or a disc ridger formation of disc blades or a disc ditcher formation of disc blades and to permit a reversal of any one of the said disc blade formations into their former formation; a hitch mounted on the bar for connecting the bar to the tractor.

7. In a tractor having a lift mechanism, the combination of: a disc harrow constructed to be raised or lowered by the lift mechanism and comprising a parallel series of forwardly and rearwardly extending bearing brackets, each bracket having a single rotatable disc blade mounted thereto, each blade being inclined vertically and horizontally, a bar detachably secured to the said brackets, a cantilever hitch shiftably mounted on said bar and constructed to connect said bar to a lifting lever having a fulcrum support secured in the vicinity of the front axle of the tractor.

8. A combination as defined in claim 7 in which a crank is connected with the lifting lever and is constructed to be operated by the lifting mechanism in the tractor for raising or lowering the said bar.

9. A combination as defined in claim 7 in which a link is connected to the cantilever hitch and tractor to position the said bar and disc blades.

WILLIAM FREDERICK McMAHON.
